UNITED STATES PATENT OFFICE.

JOHN T. UNDERWOOD AND LOIS M. UNDERWOOD, OF DAYTON, OHIO.

TWYER-GRAVE FOR INDIVIDUAL-GAS-PRODUCER KILNS.

1,376,843.

Specification of Letters Patent. Patented May 3, 1921.

Application filed February 18, 1920. Serial No. 359,647.

To all whom it may concern:

Be it known that we, JOHN T. UNDERWOOD and Lois M. UNDERWOOD, citizens of the United States, residing at Dayton, in the 5 county of Montgomery and State of Ohio, have invented certain new and useful Improvements in Twyer-Grates for Individual-Gas-Producer Kilns, of which the following is a specification.

This invention relates to new and useful 10 improvements in grates for furnaces and is designed primarily for use with twyer grates for furnaces of individual gas producer kilns.

More particularly, the invention relates 15 to the construction of the twyer grate, and means for removing the accumulations of ashes therefrom.

One object of the invention is to provide 20 means whereby the ashes may be removed from a stationary grate, or fuel supporting structure, from beneath the burning fuel, without displacing the fuel or seriously affecting it other than to permit it to settle 25 down upon the grate.

A further object of the invention is to provide, in connection with such an ashes 30 removing device, a simple and highly efficient grate for burning coal for the purpose of producing gas.

Other objects of the invention may appear as the device is described in detail.

Referring to the said drawings in general terms, Figure 1 is a front elevation of a 35 portion of a kiln showing the furnace. Fig. 2 is a vertical sectional elevation of the furnace of an individual gas producer kiln, parts being broken away to economize space. Fig. 3 is a top plan view of the grate removed 40 from the furnace. Fig. 4 is a sectional view on the line —4—4— of Fig. 3. Fig. 5 is a cross sectional view on the line —5—5— of Fig. 3. Fig. 6 is a side elevation of the front end of the grate showing the operating lever 45 by which the ash removers are operated, and Fig. 7 is an enlarged sectional view of a portion of the front end of the grate, on the line —7—7— of Fig. 3 showing a part 50 of the air and steam inlet pipe.

In these drawings we have illustrated one 55 embodiment of our invention and have shown the same as applied to a furnace gas producer and as comprising a stationary grate, or fuel supporting structure, which is provided, preferably, with one or more twyers and with means for forcing a cur-

rent of air through the twyers into the mass of fuel resting upon the grate. Mounted for movement over the upper surface of the fuel supporting structure, alongside the 60 twyer or twyers, is an ashes removing device of such a character that it will move the ashes from beneath the mass of burning fuel toward one end of the grate and there discharge the same without seriously affecting 65 the mass of burning fuel. It will be understood that the invention may take various forms and may be utilized with furnaces of various kinds without departing from the spirit thereof, and, therefore, that 70 the particular embodiment here illustrated has been chosen for the purposes of illustration only.

In a more particular description of the invention similar reference numerals will 75 be employed to indicate the same parts in the several views of the drawings. —1— designates the furnace of an individual gas producer kiln, and —2— is the bag-wall of said kiln. The furnace —1— is a part of the 80 kiln construction and each kiln of a series is provided in the structure thereof, with its own individual gas producer furnace or chamber.

The subject-matter of the present im- 85 provements consists of a removable twyer grate which is especially constructed to provide the necessary producer gas for burning the kiln, after which said grate may be removed to the individual furnace of an 90 other kiln of like structure, to be in a similar manner supplied with gas. The body or main part of the grate consists of a hollow bed plate or pan —3— having longitudinal side flanges —4— which rest upon ledges 95 —5— projecting from the opposite side walls of the furnace. When this pan —3— is supported on said ledges —5—, as shown in Fig. 1, the space —6— which is usually termed an ash-pit, lies below, but the ashes 100 do not enter this space. Means for removing said ashes from the grate in the front of the furnace are provided as follows: The pan —3— is imperforate and supported thereon and thereabove is a twyer plate 105 —7— which constitutes the upper part, or fuel supporting surface, of the grate and which has, in the present instance, two twyers —8— extending substantially the length thereof. The said plate —7— having the twyers —8— is rigidly secured to the pan —3— by bolts, and the number of

twyers may be increased by increasing the area of the said plate —7— as well as that of the pan —3—. In the present instance the twyers comprise openings, or slots, 5 formed in the plate 7 and having upwardly converging flanges arranged on both sides thereof. Immediately above the said twyers —8— are longitudinal bars —9— curved transversely and united to the ends of the 10 twyer plate —7—. These bars —9— or cover plates, as they may be properly termed, provide a certain space above the twyers for the air and steam to pass into the body of coal lying upon the grate and from 15 which the producer gas is generated. The grate, it will be understood, consists of the pan —3—, the twyers —8—, and the cover plates —9—, the latter being united to the twyer plate —7— at both ends —10—. In 20 the present form of the invention the ashes removers consist of endless chains —11— which are arranged parallel with the twyers and therebetween and on each side thereof and rest on the twyer plate —7—. These 25 endless chains —11— pass over sprocket wheels —12— and —13—, the former being on the outside of the front of the furnace, and the wheels —13— being within a pocket —14— in the back of the furnace or more 30 properly speaking, in the bag-wall —2—. The inner wheels —13— are mounted upon a shaft —15— which is supported in bearings —16— on the inner ends of the flanges —4— of the pan —3—, or in any suitable 35 way. The inner wheels —13— may be either sprocket wheels as shown, or grooved pulleys. The outer wheels —12— are necessarily chain wheels as they drive the chains —11— through the spaces between the 40 twyers and alongside thereof. The front sprocket wheels —12— are rigidly mounted upon a shaft —17— which is likewise mounted in the forward ends of the flanges —4— of the pan —3—. It will be understood 45 that there are two sprocket wheels —12— —13— for each chain. The said chains —11—, or rather some of the links thereof, have projected from them hooks —18— which serve to break up any clinkers that 50 may lie in the path of the moving chains when operated to remove the ashes from the grate. These hooks —18— as shown, project from every fourth link of the chain and stand upward when the upper run of each 55 chain is passing through the space between the twyers where the ashes accumulate. The said hooks —18— may be arranged differently if desired, and a greater number thereof may be employed as may be found necessary. At the front end of the grate the 60 pan —3— has a suitable opening —19— into which a steam and air pipe —20— is projected and by means of which steam and air are injected into said pan —3— below 65 the twyers. On the end of the front shaft

—17— a ratchet wheel —21— is secured, and loosely mounted on said shaft, adjacent to said ratchet wheel, is an operating lever —22—, the said lever having a pawl —23—, the end of which is adapted to engage the ratchet wheel —21— to move the shaft —17—. The double acting pawl —23— is pivoted at —24— to the operating lever —22— and has a tapered projection —25— projecting from the middle portion thereof. 70 This tapered projection —25— engages a tapered end —26— of a plunger —27— which is supported on the lever —22— and is pressed toward the tapered projection —25— of the pawl —23— by a coil spring —28—. This plunger —27— holds the pawl —23— in either position. When it is desired to reverse the movement of the chains —11— the pawl —23— is moved by hand from the position shown in Fig. 6, to bring 80 the tapered projection —25— thereof on the opposite side of the projection —26— of the plunger —27—. In operating the chains to effectually remove the clinkers and ashes from the grate, it may be necessary at times to reverse the movement of the chains, that is, to drive them rearward, therefore this means for operating the chains in either direction is provided. The end of the lever —22— has a socket which receives the end 90 of the extension lever —29— by which the chains are simultaneously operated.

The front of the furnace has a door —30— which closes the upper part of the furnace only, and leaves the lower part exposed so that the grate may be operated at will to remove the ashes from the twyer grate. 100

While we have shown and described one embodiment of our invention we wish it to be understood that we do not desire to be limited to the details thereof as various modifications may occur to a person skilled in the art.

Having described our invention, we claim— 110

1. In a device of the character described, a stationary fuel support, and an ashes removing device mounted for movement over said fuel support beneath the burning fuel thereon, and means for actuating said ashes removing device to move the ashes toward one edge of said fuel support. 115

2. In a device of the character described, a stationary fuel support and an endless conveyer having one stretch thereof arranged for movement over the upper surface of said fuel support and beneath the burning fuel supported thereby, and means for actuating said conveyer to move the ashes from beneath the fuel toward one edge 120 of said support.

3. In a device of the character described, a stationary fuel support having a twyer extending longitudinally thereof, means to force a current of air through said twyer, 130

said fuel support being arranged to permit ashes to be discharged at one end thereof, ashes removing devices mounted on opposite sides of said twyer for movement over the 5 upper surface of said stationary fuel support, and means for actuating said devices to move the ashes from beneath the burning fuel toward the discharge end of said fuel support.

10 4. In a device of the character described, a stationary fuel support having a twyer extending longitudinally thereof, means to force a current of air through said twyer, said fuel support being arranged to permit 15 ashes to be discharged at one end thereof, endless conveyers extending about said fuel support in the direction of its length and having their upper stretches arranged to move over the upper surface of said fuel 20 support on the respective sides of said twyer to move the ashes from beneath the fuel toward the discharge end of said fuel support, and means for actuating said conveyers.

5. In a device of the character described, 25 a hollow structure having an upper fuel supporting part, said part being provided with a twyer, means for forcing a current of air through said structure and said twyer, and ashes removing devices mounted for 30 movement over said fuel supporting part parallel with and on opposite sides of said twyer, and means for actuating said ashes removing devices to cause the ashes to be moved from beneath the burning fuel to 35 ward one end of said hollow structure.

6. In a device of the character described, 40 a stationary pan, a fuel supporting plate rigidly secured to said pan and having twyer openings extending longitudinally thereof, 45 covers extending over said twyer openings, chains arranged to travel through the spaces between adjacent twyer openings and lengthwise thereof to remove the ashes from said fuel supporting plate, and means for driving said chains.

7. In a device of the character described, 50 a fuel supporting structure comprising a pan-shaped plate having its concave side

upward, a second plate mounted on said pan-shaped plate and provided with twyer 50 openings, said pan-shaped plate having an opening in one wall thereof, an injector extending into said opening, chains movable over the upper surface of said second plate alongside of said twyer openings, 55 wheels supporting said chains and arranged at the ends of said structure, and means for simultaneously actuating the wheels at one end of said structure.

8. In a device of the character described, 60 a fuel supporting structure comprising a pan-shaped plate having its concave side upward and having marginal flanges adapted to be supported by the walls of a furnace, a second plate mounted on the first 65 mentioned plate and provided with twyer openings, an injector communicating with said pan-shaped plate, endless chains mounted for movement over the upper surface of said last mentioned plate alongside of said 70 twyer openings, and having projections thereon, and means for actuating said chains.

9. In a device of the character described, 75 a fuel supporting structure comprising a pan-shaped plate having its concave side upward and having marginal flanges to rest upon the side walls of the furnace, a second plate mounted on the first mentioned plate and having twyer openings therein, bars 80 lying above said twyer openings to form covers therefor, an injector communicating with the interior of said pan-shaped plate beneath said second plate, endless chains adapted to travel over the upper surface of said second plate alongside of said twyer 85 openings, said chains having projections extending therefrom, said pan-shaped plate having bearings at the respective ends thereof, shafts journaled in said bearings, 90 wheels mounted on said shafts to support said chains, and means for rotating one of said shafts to drive said chains.

In testimony whereof we affix our signatures.

JOHN T. UNDERWOOD.
LOIS M. UNDERWOOD.
